UNITED STATES PATENT OFFICE.

FRANK COLLINS, OF NEW YORK, N. Y., ASSIGNOR TO MUTUAL-SUNSET LAMP MFG. CO. INC., OF NEW YORK, N. Y., A CORPORATION OF NEW YORK.

DESIGN FOR METAL LACING.

Application filed March 28, 1928. Serial No. 26,049. Term of patent 3½ years.

To all whom it may concern:

Be it known that I, FRANK COLLINS, a citizen of the United States, residing in New York, in the county of New York and State of New York, have invented a new, original, and ornamental Design for Metal Lacing, of which the following is a specification, reference being had to the accompanying drawing, forming part thereof.

Fig. 1 is a plan view of a strip of metal lacing showing my new design, and

Fig. 2 is a horizontal sectional view on a line corresponding to line 2—2, Fig. 1, showing the lacing in use as connecting two adjacent panel elements.

I claim:

The ornamental design for metal lacing, as shown.

FRANK COLLINS.
